FOUNTAIN

Thomas M. Hibben, 180 Old Farm Road,
Northbrook, Ill. 60062

Original design application Apr. 21, 1967, Ser. No. 6,778.
Divided and this application Feb. 28, 1968, Ser. No.
12,063

Term of patent 14 years

Int. Cl. D23—01

U.S. Cl. D23—13

FIG. 1 is a perspective view of a fountain showing my design;

FIG. 2 is a front elevational view thereof; and
FIG. 3 is a top plan view thereof.

The dominant features of my design are shown in full lines.

This is a division of design application Ser. No. D.6,778, filed Apr. 21, 1967.

I claim:

The ornamental design for a fountain, substantially as shown and described.
